UNITED STATES PATENT OFFICE.

HARRY L. DIEHL, OF CHICAGO, ILLINOIS.

DESIGN FOR A BADGE.

No. 39,134.

Specification for Design.

Patented Feb. 18, 1908.

Application filed November 8, 1907. Serial No. 401,345. Term of patent 7 years.

To all whom it may concern:

Be it known that I, HARRY L. DIEHL, a citizen of the United States, residing at Chicago, Cook county, Illinois, have invented a new, original, and ornamental Design for Badges, of which the following is a specification, reference being had to the accompanying drawing, forming a part hereof.

The figure is a face view of a badge showing my new design.

I claim:
The ornamental design for a badge as shown.

HARRY L. DIEHL.
